[57] **ABSTRACT**

In an electromagnetic switching apparatus including a housing, stationary and movable electrical contacts disposed therein, a movable magnetic switching member disposed with the movable contacts on a carrier bridge, a non-movable magnetic non-switching member on which the excitation coil and coil form of the apparatus are disposed, and elongated support rods each having resilient grommets disposed thereon for mounting the non-movable magnetic member in the housing, the improvement comprising lateral mounting members extending outwardly from opposing sides of the non-movable member, having longitudinal apertures for receiving the rods and grommets and thereby resiliently mounting the non-movable member within the apparatus housing. In addition, the grommets may include planar shaped support portions for resiliently mounting the coil form, the resilient layer members or leaf springs may be provided for biasing the coil form towards the non-movable member and further resiliently mounting the latter. Removable mounting brackets for both the leaf springs and return springs for the movable magnetic member may also be provided.

RESILIENT MOUNTING ARRANGEMENT FOR THE NON-MOVABLE MAGNETIC MEMBER OF AN ELECTROMAGNETIC SWITCHING APPARATUS

BACKGROUND OF THE INVENTION

1. Field of the Invention

This invention relates generally to electromagnetic switching apparatus, and in particular to an improved resilient type mounting arrangement for the non-movable magnetic member of such an apparatus.

2. Description of the Prior Art

Resilient type mounting arrangements for the non-movable magnetic member of an electromagnetic switching apparatus are generally known in the art. German Auslegeschrift No. 1,259,439, for example, discloses an electromagnetic switching apparatus in which a pair of support rods, each having a length greater than that of the non-movable magnetic member of the apparatus, are disposed through apertures provided therein for supporting the non-movable magnetic member in the apparatus housing. Grommets fabricated from rubber or another resilient material are disposed on the support rods between the latter and the non-movable member to provide a resilient mount for the magnetic member. The thickness of the support rods in such an arrangement is limited, however, and the surface area thereof contacting the grommets is small. Thus, the choice of the types of resilient materials from which the grommets may be fabricated is limited by the surface area of the rods available for engagement with the grommets with respect to the resiliency of the mount desired for the non-movable magnetic member. It is desireable, however, that the resilient mount be so designed that the choice of resilient type materials which may be utilized to fabricate the grommets is greatly increased and the resiliency of the mount desired for the non-movable member and the resiliency of the material used to fabricate the grommets can be better coordinated.

SUMMARY OF THE INVENTION

It is therefore an object of the invention to provide an improved resilient type mounting arrangement for the non-movable magnetic member of an electromagnetic switching apparatus which overcomes the above-described disadvantages of heretofore known arrangements.

These and other objects are achieved in an electromagnetic switching apparatus which includes a housing; stationary and movable electrical contacts disposed therein; a movable magnetic switching member disposed with the movable electrical contacts on a carrier bridge; a non-movable magnetic non-switching member on which the excitation coil and coil form of the apparatus are disposed; and elongated support rods each having resilient grommets disposed thereon for mounting the non-movable magnetic member in the housing of the apparatus. The improvement of the invention comprises the provision of lateral mounting members which are coupled to and extend outwardly from opposing sides of the non-movable magnetic member. These mounting members include elongated apertures extending longitudinally therethrough for receiving said support rods and grommets, and thereby resiliently mount the non-movable magnetic member in the apparatus housing.

In other embodiments of the invention, the grommets may include an outwardly extending planar-shaped portion, disposed substantially parallel to the longitudinal axis thereof, for supporting the coil form in a resilient manner within the housing. A plurality of resilient layer members may also be interposed between the coil form and the apparatus housing opposite the grommets for further resiliently mounting the non-movable magnetic member. Instead of the layer members, spring means may be utilized to further resiliently mount the non-movable member within the housing and bias the coil form towards the member. Removable mounting brackets, having threaded apertures for coupling thereto an auxiliary switching apparatus are utilized to mount both the spring means and return springs for the movable magnetic member within the housing.

These and other features of the invention, and the advantages thereof, will be described in detail in the following detailed description.

BRIEF DESCRIPTION OF THE DRAWINGS

FIG. 1 is a front view, partly in section, of an electromagnetic switching apparatus constructed according to the invention;

FIG. 2 is a side view, partly in section, of the apparatus of FIG. 1;

FIG. 3 is a top cross-sectional view of the apparatus illustrated in FIGS. 1 and 2;

FIG. 4 is an end view of a resilient grommet constructed according to the invention;

FIG. 5 is a longitudinal, cross-sectional view of the grommet of FIG. 4;

FIG. 6 is a top plan view of the grommet shown in FIGS. 4 and 5;

FIG. 7 is a side view of a movable mounting bracket constructed according to the invention;

FIG. 8 is a top plan view of the bracket of FIG. 7; and

FIG. 9 is an end view of the bracket shown in FIGS. 7 and 8.

DETAILED DESCRIPTION

Referring now to the drawings, in particular to FIGS. 1-3, there is shown an electromagnetic switching apparatus comprising a housing, generally designated 1, in which stationary and movable electrical contacts, 2 and 2a, respectively, are disposed. An arc quenching arrangement, generally designated 3, of known type is provided for extinguishing current arcs produced during opening of the switching apparatus. A movable magnetic switching member 4 is disposed with movable contacts 2a and a contact bridge 5 on a movable carrier bridge 6. A non-movable magnetic non-switching member 7 is disposed therebelow in housing 1 and supports a coil 8 and excitation coil 9 therein. Elongated cylindrical support rods 11, each of which have resilient grommets 12 disposed thereon, are disposed through a pair of lateral mounting members 10 which are integrally formed with the non-movable magnetic member on opposing sides thereof. Members 10 include longitudinal apertures for receiving rods 11 and grommets 12 and thereby providing a resilient mount for member 10 in housing 1. Each of the support rods 11 is coupled to a base plate 14 in housing 1 by means of a fastening screw 15 and a pair of bearing blocks 13 coupled thereto.

As shown in FIGS. 4-6, each of grommets 12 include an annular flange 29 and may be provided with an out-

wardly extending planar-shaped, rectangular portion 16 integrally formed therewith for supporting coil form 8 and coil 9 in a resilient manner within housing 1. Portion 16 is disposed substantially parallel to the longitudinal axis of grommet 12 in a recess 17 provided in coil form 8 and serves as a seat for the latter on member 10. Portion 16 also engages the top surface of lateral mounting member 10, the latter being received as shown in FIG. 1 in the slot formed by the portion between itself and the body of the grommet. This grommet construction greatly simplifies the switching apparatus configuration by reducing the number of parts which are required for mounting the apparatus components within housing 1.

In order to further resiliently mount member 10 in housing 1, and bias coil 8 towards member 10 and portions 16, a plurality of layer members 30, fabricated from resilient material, are interposed between housing 1 and coil form 8 opposite grommets 12 and portions 16. These layer members may be replaced, if desired, by spring means, illustrated as leaf springs 18, laterally displaced with respect to grommets 12 and joined by means of a rivet connection 20 to a removable mounting means, illustrated as mounting brackets 19, which are slidably disposable in housing 1. As shown in detail in FIGS. 7-9, bracket 19 is U-shaped and is provided with sheared-out lugs 21 which detent in a slot 22 in housing 1 to secure bracket 19 therein, and a support portion 23 disposed perpendicular to the surface of the bracket for the return spring 24 of movable magnetic member 4. Threaded apertures 25 are provided for receiving the fastening screws 26 of an auxiliary switch extension 27 (see FIG. 2), thereby assuring a secure attachment of the switches even in a housing having a relatively thin wall. Each of springs 18 engages a hook type projection 28 formed on coil form 8 and is flexed into the position illustrated by the dotted lines in FIG. 1 when the base plate of the apparatus is secured in place. Coil form 8 is thus pushed against portions 16 of the grommets 12. Brackets 19 also simplify the construction of the switching apparatus in that no separate mounting brackets are necessary for both the return springs 24 and leaf springs 18.

In the foregoing specification, the invention has been described with reference to specific exemplary embodiments thereof. It will, however, be evident, that various modifications and changes may be made thereunto without departing from the broader spirit and scope of the invention as set forth in the appended claims. The specification and drawings are, accordingly, to be regarded in an illustrative rather than in a restrictive sense.

What is claimed is:

1. In an electromagnetic switching apparatus including a housing, stationary and movable electrical contacts disposed therein, a movable magnetic member disposed with the movable electrical contacts on a carrier bridge, a U-shaped non-movable magnetic member

on which the excitation coil and coil form of the apparatus are disposed, and elongated support rods having resilient grommets disposed thereon for mounting the non-movable magnetic member in the apparatus housing, the improvement comprising,

mounting members, integrally formed with and extending laterally outward from opposing sides of said non-movable magnetic member beyond the base thereof, said mounting members comprising part of said non-movable magnetic member and including elongated apertures extending longitudinally therethrough in which said grommets are inserted for resiliently mounting said non-movable magnetic member in said housing.

2. In an electromagnetic switching apparatus including a housing, stationary and movable electrical contacts disposed therein, a movable magnetic member disposed with the movable electrical contacts on a carrier bridge, a non-movable magnetic member on which the excitation coil and coil form of the apparatus are disposed, and elongated support rods having resilient grommets disposed thereon for mounting the non-movable magnetic member in the apparatus housing, the improvement comprising,

lateral mounting members, coupled to and extending outwardly from opposing sides of said non-movable magnetic member, said members including elongated apertures extending longitudinally therethrough for receiving said support rods and grommets and thereby resiliently mounting said non-movable magnetic member in said housing, and said grommets each including an outwardly extending portion joined thereto resiliently supporting said coil form within said housing.

3. The apparatus recited in claim 2, wherein said outwardly extending portion is planar shaped and is disposed substantially parallel to the longitudinal axis of the grommet to which it is joined.

4. The apparatus recited in claim 2, further comprising a plurality of resilient layer members interposed between said coil form and said housing opposite said grommets.

5. The apparatus recited in claim 2, further comprising spring means disposed within said housing for biasing said coil form towards said non-movable magnetic member.

6. The apparatus recited in claim 5, further comprising removable mounting means, slidably disposed within said housing, and coupled to said spring means, for mounting said spring means and return springs for said movable magnetic member within said housing.

7. The apparatus recited in claim 6, wherein said removable mounting means comprise mounting brackets having threaded apertures disposed therein for receiving mounting screws for an auxiliary switching apparatus.
